SINGLE DECK CONTACT TYPE FLOATING ROOF

Frederick D. Moyer, Chicago, and Clifford M. Orr, Western Springs, Ill., assignors to Chicago Bridge & Iron Company, a corporation of Illinois

Application October 12, 1954, Serial No. 461,718

5 Claims. (Cl. 220—26)

This invention relates to a tank floating roof of the single deck contact type.

In such a roof, the contour of the lower face of the deck, which under normal floating conditions is entirely in contact with the liquid upon which it floats, is the same as the upper drainage area or surface of the deck, 20 the upper and lower faces being separated only by the thickness of the deck plates.

One of the main problems with such a roof is drainage of surface rainfall. In order to have adequate drainage it is important to have appropriate slope or pitch, but the pitch of the roof is limited specifically by the weight of the roof and the specific gravity of any given liquid on which it floats. This is because more liquid is displaced as the slope increases and with any given roof weight and any given specific gravity of liquid, the entire under surface of the roof can no longer be immersed in the liquid when the slope has been increased to an efficient pitch.

It has been suggested in the past that heavy weights be concentrated at or near the center of the roof so that it can be further immersed, but this adds more problems than it solves.

In the present invention the problem is solved, without the addition of unnecessary weight, by providing steps in vertical cross section to provide a plurality of integrated drainage areas, the steepness of the slope in at least one of such areas, and preferably in all, substantially exceeding the steepness of the slope possible with a single drainage area on a roof of the same size and weight.

In one form of the invention the drainage areas comprise a plurality of concentric annuli, with drains connecting the ring drainage area formed at the junctions of the annuli with a central drainage area.

In another form of the invention the drainage areas are radial, comprising radial wedges sloped to provide radial drainage areas between them.

It is also possible to combine these forms of drainage areas.

The invention is illustrated in the drawings, in which:

Figure 1 is a partial plan view of one form of the roof (stiffeners or trusses omitted);

Figure 2 is a vertical section taken along the line 2—2 in Figure 1 (stiffeners or trusses omitted);

Figure 3 is a vertical section taken along the line 3—3 in Figure 1 (stiffeners or trusses omitted);

Figure 4 is a developed vertical cylindrical section taken along the line 4—4 in Figure 1;

Figure 5 is a partial plan view of a modified form of the invention;

Figure 6 is a section taken along the line 6—6 in Figure 5;

Figure 7 is a partial plan view of a modified form of the invention;

Figure 8 is a vertical section taken along the line 8—8 in Figure 7 (stiffeners omitted);

2

Figure 9 is a partial plan view of a modified form of the invention;

Figure 10 is a section taken along the line 10—10 in Figure 9 (stiffeners omitted);

Figure 11 is a partial plan view of another form of the invention (stiffeners included); and

Figure 12 is a section taken along the line 12—12 in Figure 11.

The first successful floating roofs were of the "pan" or pontoon-less type. This is the most economical type of floating roof and is widely used today for crude oils and products of relatively low volatility which require reduction of filling losses, prevention of corrosion from "sour" liquids and protection against losses from fire, but do not require the additional insulation of a pontoon or double deck type of roof.

Such a roof must be of the "contact" type—that is, it must float with the entire underside of the roof wetted by the stored product, if corrosion of the roof is to be reduced to the minimum. It must also be pitched for drainage of rain water because the roof, having no stabilizing pontoons, is subject to tipping and even sinking if a large quantity of water is allowed to collect on the deck.

In the past most pan roofs were built with the single-thickness deck plates shaped by widely-spaced trusses into approximately conical form, the cone sloping uniformly downward from the outer rim to a sump near the center of the roof. The weight of the stored liquid displaced by this cone was, of course, equal to the floating weight of the roof, but since the liquids were likely to be relatively heavy, sometimes approaching the weight of water, and since this simplest type of roof was relatively light compared with pontoon-type or double-deck-type roofs, the slope of the cone even when shaped by the mentioned trusses, was nevertheless quite flat and drainage of rain water was not always satisfactory.

Structurally, the conical shape was far from ideal, for the heavy outer portion of the roof displaced much less than its weight while the central portion displaced more than its weight thus creating a tendency for the center of the roof to be displaced upwards compared with the outer portion, destroying adequate drainage. The roof, therefore, had to be held in this conical shape by heavy trusses.

As an example, the slope from rim to center for a roof in a tank 140 feet in diameter might be about 7 inches, and the drainage pitch thus only 7 inches in approximately 70 feet, or one inch in approximately 10 feet. Roofs usually were built of lap-jointed plates of $\frac{3}{16}$ inch thickness which, without any trussing or supports, weighed about 8 pounds per square foot and thus tended to displace more than $1\frac{1}{4}$ inches of a product weighing 54 pounds per cubic foot. Since the slope of the conical deck was about one inch in 10 feet, the weight of steel was greater than the theoretical displacement for an outer annular portion of the deck nearly 18 feet wide, and this portion tended to sag between trusses. Furthermore, a large portion of the weight of a pan roof was made up of the devices used to seal the space between the outer rim of the roof and the tank shell, and the outer rim itself was a heavy plate, so the trusses had to lift these outer loads, including the weight of the outer deck plates not balanced by displacement, and transfer them toward the center of the roof where the displacement exceeded the weight.

The result was that not only did the roof drain poorly because of insufficient pitch and the other reasons listed, but also the trussing provided for forcing the roof into shape had to be designed for large loads.

There were other disadvantages of the old design.

When a tank was emptied, the roof could not be allowed to come to rest directly on the tank bottom because it was not the same shape as the bottom, and further because a drain pipe and other devices beneath the roof required clearance. Therefore, it was necessary to provide a structure for landing the roof in its low position; and since this supporting structure carried not only the weight of the roof but also the weight of water, snow and ice that accumulated while the roof was landed, it was a heavy and costly structure. Usually it consisted of a large number of individual leg supports, the large number being required because each leg was connected only to the single-thickness deck plates and the load per support was limited by the strength of the deck plates and the firmness of the grade on which the deck plates rested.

Another disadvantage of the original design of pan floating roof was the difficulty of assembling and joining the deck plates. Neither the trusses nor the supports, alone or in combination, could be used for supporting the individual deck plates when the roof was being built. The trusses were too widely spaced to hold the plates in proper shape, and the leg supports tended to distort the unstiffened deck plates near the supports.

The present floating roof design has the following advantages:

(1) Improved drainage with positive radial or circumferential pitch or both radial and circumferential pitch toward the sump.

(2) Improved trussing with adequate circumferential as well as radial framing.

(3) Reduced bending moments due to improved location of buoyancy with respect to weight. This is partially responsible for the reduction in the cost of trussing.

(4) Reduced erection cost due to elimination of heavy temporary supports for construction.

(5) In some cases a smaller number of adjustable supports and more positive load distribution on supports resulting from use of circumferential framing.

It is contemplated that the high portions formed by the steps be vented since it is not normally desired to collect gas in these high spots. The form of vents, however, is no part of the present invention.

In Figures 1, 2, 3 and 4 the wedge-shaped stepping is illustrated.

As there shown, a floating roof 10 is divided into a number of pie-shaped wedges or segments 11. These are divided alternately by ridges 12 and valleys 13. In this form of the invention the drainage areas are generally warped having constantly changing pitch and all of the drainage follows the valleys 13 to the central sump 14 from which a drain 15 leads to the bottom of the tank.

In Figures 5 and 6, a form of the invention in which a plurality of annuli is used is illustrated. In this form the single deck portion is divided into an outer annulus 20 and an inner annulus 21 separated by the step 22. A drain trough 23 connects the lowermost portion of the annular segment 20 with the central drain sump. It is of course to be appreciated that the slope of the central conical portion can be reversed so that the step 22 is eliminated at that point, but a double slope is again provided. As in the previous case, troughs leading into a central trough 14 and drain 15 are provided.

Although a central sump is shown in the figures, it should also be understood that a sump located elsewhere will work with only slightly reduced efficiency. It should be noted that the troughs leading from the annular portions of the roof to the sump do not add significantly to the displacement of liquid.

In Figures 7 and 8, a modified form is shown in which a pontoon 25 is provided in combination with a single deck of the contact type having annuli 20 and 21. Similarly, single decks of the contact type as shown in the other figures may be combined with a pontoon.

Figures 9 and 10 illustrate a combination form in which the single deck portion comprises a central con-

ical portion 30, which may be considered as an annulus surrounding and sloping inwardly toward the sump 14 and the radial segments 32 which in combination with each other form alternate ridges 33 and valleys 34.

5 Drainage of the radial segments 32 is to the ring drainage area 31 which is connected by a series of troughs 35 to the central sump.

Figures 11 and 12 are detailed fragmentary views illustrating another form of the invention having three 10 annular areas 60, 61 and 62 separated by steps 63, 64 and 65. Drainage is to the central sump 66.

Trussing is accomplished by means of the rafters 70, 71 and 72 and posts 73, 74 and 75. These are connected by conventional rods 76, 77, 78 and 79. Similar trussing may be provided in the other forms of the invention though not shown.

In the particular form illustrated in Figures 11 and 12, the annuli 60 and 61 are 20 feet wide; the annulus 62 is 25 feet wide; and the sump is 4 feet in radius. This 15 roof will accommodate a 140 foot tank.

The outer annulus 60 has pitch of 5 inches; annulus 61 has a pitch of 5 inches; and annulus 62 has a pitch of 7 inches. All of these are steeper than the pitch that could be accomplished by using a single cone of the same size and weight floating on the same liquid and in contact therewith and could be increased further by adding the ridge and valley construction shown in Figures 1, 2, 25 3, 4, 8, 9 and 10.

The above detailed description has been given for 30 clearness of understanding only and no unnecessary limitations should be understood therefrom as modifications will be obvious to those skilled in the art.

We claim:

1. A floating roof of the contact type for a liquid storage tank comprising a single roof deck portion to cover liquid in the tank, the lower surface of the roof deck being adapted to remain substantially completely in contact with the liquid in the tank, said roof deck having portions sloped transversely to a radius of the roof and portions sloped radially toward the center of the roof to divide the upper surface thereof into drainage areas converging toward the center of the roof, said drainage areas comprising a plurality of concentric annuli forming at least one ring-like drainage trough, a central outlet to receive the drainage from the converging drainage areas, a communicating passage from said trough to said central drainage outlet, said communicating passage being adapted to permit gravity flow of surface liquid from said trough to said outlet, the total effective slope of each drainage area exceeding the maximum slope possible in a continuous single deck roof of substantially the same weight and size having its lower surface maintained substantially in contact with the liquid in the tank.

2. A floating roof of the contact type for a liquid storage tank comprising a single roof deck portion to cover liquid in the tank, the lower surface of the roof deck being adapted to remain substantially completely in contact with the liquid in the tank, said roof deck having portions sloped transversely to a radius of the roof and portions sloped radially toward the center of the roof to divide the upper surface thereof into drainage areas converging toward the center of the roof, said drainage areas comprising a plurality of concentric annuli forming at least one ring-like drainage trough, a central outlet to receive the drainage from the converging drainage areas, a communicating passage from said trough to said central drainage outlet, said communicating passage being adapted to permit gravity flow of surface liquid from said trough to said outlet, and an annular pontoon portion surrounding and in contact with the outer edge of the roof deck, the total effective slope of each drainage area exceeding the maximum slope possible in a continuous single deck roof of substantially the same weight and

size having its lower surface maintained substantially in contact with the liquid in the tank.

3. A floating roof of the contact type for a liquid storage tank comprising a single roof deck portion to cover liquid in the tank, the lower surface of the roof deck being adapted to remain substantially completely in contact with the liquid in the tank, said roof deck having portions adapted to be drained in directions transverse to a radius of the roof and portions adapted to be drained along radii toward the center of the roof to divide the upper surface thereof into drainage areas converging toward the center of the roof, said drainage areas comprising a plurality of concentric annuli forming at least one ring-like drainage trough, a central outlet to receive the drainage from the converging drainage areas, a communicating passage from said trough to said central drainage outlet, said communicating passage being adapted to permit gravity flow of surface liquid from said trough to said outlet, the total effective slope of each drainage area exceeding the maximum slope possible in a continuous single deck roof of substantially the same weight and size having its lower surface maintained substantially in contact with the liquid in the tank.

4. A floating roof of the contact type for a liquid storage tank comprising a single roof deck portion to cover liquid in the tank, the lower surface of the roof deck being adapted to remain substantially completely in contact with the liquid in the tank, said roof deck having a plurality of concentric annular drainage troughs with the outer periphery of one adjacent to the inner periphery of the other, the outer annular trough being adapted to drain toward the roof center and to have the

accumulation then drain transversely to a radius of the roof and turn downwardly toward the inner annular trough, said inner trough having portions sloped radially toward the center of the roof to divide the upper surface thereof into drainage areas converging toward the center of the roof, a central outlet to receive the drainage from the converging drainage areas, a communicating passage leading from the inner annular trough to said drainage outlet, the flow from each annular trough being gravitational to provide a final drainage of the roof at its center, the total effective slope of each drainage area exceeding the maximum slope possible in a continuous single deck roof of substantially the same weight and size having its lower surface maintained substantially in contact with the liquid in the tank.

5. The floating roof claimed in claim 4 comprising in addition a generally annularly shaped pontoon positioned in contact with the outer annular trough and having its inner periphery in engagement with the outer periphery 20 of the outer trough.
